UNITED STATES PATENT OFFICE.

JAMES I. HEALEY, OF BROOKLYN, NEW YORK.

DESIGN FOR NEWEL-POST.

Specification forming part of Design No. **11,124**, dated March 25, 1879; application filed February 24, 1879.
[Term of patent 3½ years.]

To all whom it may concern:

Be it known that I, JAMES I. HEALEY, of Brooklyn, in the county of Kings and State of New York, have originated and invented a new and useful Design of Newel-Post; and I do hereby declare that the following is a full, clear, and exact description thereof, reference being had to the accompanying drawing, forming a part of this specification.

The object or purpose of the present invention is to provide a design for a newel-post with an ornamental head supporting a vase or urn, also with an ornamental base and side panels, as will be hereinafter described, and subsequently pointed out in the claims.

The accompanying drawing, which represents a perspective view of a newel-post, has a base, A, consisting of the flat-faced moldings *a* *b* and round-faced molding *c*. The sides or panels of the post have a circular flower, *f*, and above this a double leaf, *e*, the corners of the sides or panels being flattened, as shown at *k*, and joining near the base A with an ornamental shoulder, *d*. Above the double leaf *e* are beads *g*, and between the beads are flutes *h*. The head B consists of the ornamental scrolls *i*, with rosettes *l*, the head having a covered vase or urn, *m*, encircled

with leaves *n*, and terminating at its top in a finial, *p*.

Having now fully described my invention, what I claim as new, and desire to secure by Letters Patent, is—

1. A design for the top of a newel-post, consisting of the head B, with ornamental scrolls *i*, rosettes *l*, covered vase or urn *m*, with leaves *n*, and finial *p*, substantially as specified.
2. A design for the sides or panels of a newel-post, consisting of the circular flower *f*, double leaf *e*, fluted surface *h*, and beads *g*, as specified.
3. A design for newel-posts, consisting of the base A, flattened corners *k*, shoulder *d*, flower *f*, double leaf *e*, fluted surface *h*, beads *g*, ornamental head B, vase or urn *m*, with leaves *n*, and finial *p*, substantially as set forth.

In testimony that I claim the foregoing as my own I affix my signature in presence of two witnesses.

JAMES INGALLS HEALEY.
